UNITED STATES PATENT OFFICE.

ALBERT GAPINSKI, OF CARNEGIE, PENNSYLVANIA.

CAR-COUPING.

No. 826,287.

Specification of Letters Patent.

Patented July 17, 1906.

Application filed March 28, 1906. Serial No. 308,463.

To all whom it may concern:

Be it known that I, ALBERT GAPINSKI, a citizen of the United States of America, residing at Carnegie, in the county of Allegheny and State of Pennsylvania, have invented certain new and useful Improvements in Car-Couplings, of which the following is a specification, reference being had therein to the accompanying drawings.

- 10 This invention relates to certain new and useful improvements in car-couplings; and the invention relates more particularly to a coupling adapted to be used in connection with pit-cars of mines.
- 15 The primary object of this invention is to provide a novel form of automatic coupling for pit-cars wherein positive and reliable means are employed for gripping a coupling bar or link.
- 20 Another object of this invention is the provision of novel means for normally maintaining a coupling bar or link in alignment with the draw-bar or center girder of a car, thus normally holding the coupling bar or link in position to enter the coupler of the adjoining car.
- 25 A further object of this invention is to provide a simple and inexpensive coupler for pit-cars which will be positive in its action and free from all danger of being injured by constant use.

With the above and other objects in view, which will more readily appear as the nature of the invention is better understood, the same consists in the novel construction, combination, and arrangement of parts to be hereinafter more fully described and claimed, and, referring to the drawings accompanying this application, like numerals of reference 35 designate corresponding parts throughout the several views, in which—

Figure 1 is a side elevation of my improved coupler, illustrating a portion of two pit-cars connected together. Fig. 2 is a plan of my improved coupler, illustrating a coupling bar or link therein. Fig. 3 is a side elevation of a coupling bar or link. Fig. 4 is a plan of the bottommost section of my improved coupling. Fig. 5 is a bottom plan of the uppermost section of my improved coupling. Fig. 6 is a longitudinal sectional view of the same. Fig. 7 is a similar view of the lowermost section of the coupling. Fig. 8 is a cross-sectional view taken on the line $x-x$ of Fig. 6. Fig. 9 is a similar view taken on the line $y-y$ of Fig. 4, and Fig. 10 is a perspective view of the coup-

ling-pin. Fig. 11 is a transverse vertical sectional view of the coupling-pin shown in detail in Fig. 10.

To put my invention into practice, I construct my improved coupling of two sections, an upper section 1 and a lower section 2. These sections are adapted to fit together, and they have their confronting faces recessed, as at 3 and 4, to form a pocket for the end of a coupling bar or link 5^a. The confronting faces of the sections 1 and 2 at the opposite end of said sections is also recessed, as at 5 5, to permit of the sections being clamped together upon the end beam 6 of a car 7. The same ends of the sections 1 and 2 are further recessed, as at 8 8, to receive the end of the draw-bar (not shown) of a car.

In securing the sections 1 and 2 together I provide the section 2 with upwardly-extending dowel-pins 9 9 and 10 10, adapted to fit in openings or recesses 11 11 and 12 12, respectively, of the upper section 1 of the coupling. The dowel-pins serve to correctly position the sections 1 and 2, and in securing them together I employ bolts and nuts 14, the bolts and nuts being arranged to firmly clamp the sections of a coupling upon the beam 6 and the draw-bar, also to firmly hold said sections together. In recessing the sections 1 and 2, as at 3 and 4, I provide the upper section 1 with a vertically-disposed recess or pocket 15 to receive a coupling-pin 16. The coupling-pin 16 consists of a transverse bar 17, having a beveled edge 18, said bar at its ends being provided with depending arms 19 19, these arms engaging in slots 20 20, formed in the section 2, when the coupling-pin is lowered or in a locked position. To manipulate the coupling-pin 16, the transverse bar 17 is provided with an upwardly-extending pin or rod 21, which passes through an opening 22, formed in the upper section 1 of the coupling.

The sections 1 and 2 of the coupling have their confronting faces equally recessed to form spring-pockets 23 23 and presser-arm pockets 24 24. In the latter pockets are mounted angular resilient presser-arms 25 25, which are engaged by springs 26 26, mounted in the former pockets. The resiliently-mounted presser-arms 25 are pivotally mounted in their respective pockets by one of the nuts and bolts 14, which are employed for retaining the sections 1 and 2 of the coupling together.

The coupling bar or link 5^a, which I em-

ploy in connection with my improved coupling, is provided with two recesses or transverse grooves 27 27 adjacent each end, the ends of said bar or link being beveled upon 5 all four sides, as at 28.

In operation when the coupling bar or link 5^a enters the coupling the upper beveled face of the bar, together with the beveled face or edge 18 of the pin 16, causes the pin 16 to rise 10 until the bar has passed into the coupler between the presser-arms 25 25. As the pin 16 rides over the beveled end of the bar 5^a it finally reaches one of the recesses or grooves 27 of said bar and drops into said recess or 15 groove, locking the coupling bar or link within the coupler. The presser-arms 25 25 serve in maintaining the coupling bar or link 5^a centrally of the coupling, also in returning the coupler bar or link to its normal position 20 should it be moved to one side. To uncouple two cars connected together, it is only necessary to elevate one of the pins 16 through the medium of a link 29, carried by said pin, at which time the cars may be separated.

25 My improved coupler is preferably constructed of strong and durable metal, and in making the same in two sections one of said sections can be renewed irrespective of the other, this also being true of the pin 16, which 30 can be renewed by simply separating the sections of the coupling.

Such changes in the construction and operation of my improved coupling as are permissible by the appended claims may be resorted 35 to without departing from the spirit and scope of the invention.

What I claim, and desire to secure by Letters Patent, is—

1. A coupler for pit-cars consisting of two 40 sections detachably secured together, the confronting faces of said sections being equally recessed to form pockets, spring-pressed arms pivotally mounted in one of said sections, a coupling-pin mounted in the other of 45 said sections and adapted to engage in the first-named section, a coupling-bar adapted to engage between said arms, said bar having grooves formed therein, substantially as described.

50 2. In a car-coupler, two similar sections or members adapted to match together, means for securing said sections together, the matching faces of said sections being recessed to receive the end of a beam to which they are secured, said matching faces having pockets, 55 spring-pressed arms pivotally mounted in the pockets of one section, dowel-pins carried by the matching face of one of said sections and engaging in recesses provided therefor in the matching face of the opposite sec-

tion, both of said sections recessed at their forward ends to permit the entry of a coupling-link, and a coupling-pin comprising a bar movable vertically in a recess in the uppermost section, and having depending arms 65 adapted to engage in recesses provided therefor in the lowermost section.

3. In a car-coupler, two coupling-sections matched together, dowel-pins carried by the matching face of one section and engaging in 70 recesses provided therefor in the matching face of the other section, bolts securing said sections together, and each section being recessed at its forward end to permit the entry of a coupling-link, in combination with a 75 coupling-pin comprising a transverse bar movable vertically in a recess provided therefor in one of said sections and having depending arms to engage in recesses provided therefor in the other of said sections, said bar having a stem extending through the section in which the bar is movable.

4. In a car-coupler, two matching sections secured together, each section provided with recesses on its matching face, and having recesses in its forward end to permit the entry of a coupling-link between the sections, spring-pressed arms arranged within one of said sections to guide said link, and a coupling-pin to engage with said link, said pin 85 comprising a bar arranged to move in a recess provided therefor in the uppermost section, and having depending arms to engage in recesses provided therefor in the lowermost section.

5. A coupling for pit-cars, comprising a body formed in two sections, secured together and recessed at their rear ends to receive a pit-car car-beam, the said sections being recessed at their forward ends to permit the 100 entry of a coupling-link, dowel-pins carried by one of said sections to engage in recesses provided therefor in the other of said sections and spring-pressed arms within the body to guide said coupling-link, in combination with 105 a coupling-link having a transverse groove, and a coupling-pin to engage said link and comprising a bar movable in a recess in one of the sections and adapted when in lowered position to engage in the transverse groove of 110 the link, said bar carrying arms to engage in recesses provided therefor in the lowermost section of the body.

In testimony whereof I affix my signature in the presence of two witnesses.

ALBERT GAPINSKI.
